(57) **CLAIM**

The ornamental design for a doll, as shown.

DESCRIPTION

FIG. 1 is a perspective view of a doll that has the design, in a seated position.

FIG. 2 is a front view of the doll in an alternate position.

FIG. 3 is a rear view of the doll in the alternate position.

FIG. 4 is a side view of the doll in the alternate position; and, FIG. 5 is an opposite side view of the doll.

The broken lines in the buttons of the doll's dress are for illustrative purposes only and form no part of the claimed design.

The broken lines on the doll's dress represent stitching and forms part of the claimed design.

1 Claim, 5 Drawing Sheets
